UNITED STATES PATENT OFFICE.

OTTO SOMMER, OF ZURICH, SWITZERLAND, ASSIGNOR TO STAUWERKE A.-G., OF ZURICH, SWITZERLAND.

MOVABLE DAM OF FERROCONCRETE.

1,382,132.

Specification of Letters Patent. Patented June 21, 1921.

Application filed July 1, 1920. Serial No. 393,242.

To all whom it may concern:

Be it known that I, OTTO SOMMER, a citizen of the Republic of Switzerland, residing at Zurich, Switzerland, have invented 5 certain new and useful Improvements in Movable Dams of Ferroconcrete; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 This invention has for its object a hollow dam of ferro-concrete pivotally supported by a fixed substructure and moved by water pressure.

Reference is to be made to the accompanying drawings, forming a part of this specification, in which similar characters of reference indicate corresponding parts in all the figures.

Figure 1 shows a diagrammatic cross-section of the movable hollow dam, and Fig. 2 is a radial section thereof.

Fig. 3 is a longitudinal section showing a modified construction of one of the end chambers.

30 Fig. 4 is a cross section showing the internal chambers extending over the whole cross section of the dam.

Figs. 5-7 are diagrammatic views illustrating the forming of an accurate curvature to the damming face.

Fig. 8, is a side view and Fig. 9 a cross view showing the manner of mounting the angle irons on the face of the dam.

The movable hollow dam consists of the 40 circular arch-shaped breast-wall *a*, the straight roof *b* and the partition walls *c*¹, *c*², *c*³, etc. At the crest *d* of the weir hollow spaces *f* are formed by the provision of walls *e*, said hollow spaces being closed so 45 as to be water-tight on all sides. The partition walls *c*¹, *c*², etc., thicken toward the lower end of the dam (see Fig. 2) and finally merge in a through-beam *g*, to which the axis of rotation *h* is secured. This axis 50 is supported by a bearing *i* also passing quite through the dam. The axis of rotation coincides with the center of the circular arch 1-2 or is adjacent thereto.

The whole of the hollow dam can be sunk 55 into the weir chamber *k*. Instead of mak-

ing the breast-joint *l* water tight, a narrow gap may be left, allowing a certain volume of water to enter the weir chamber.

The size of the hollow spaces *f* is such that the buoyancy produced by them, 60 conjointly with the water pressure acting upon the inner surface *b* raises the damming body as soon as the water pressure reaches a certain degree. If the water pressure diminishes in the weir chamber, the damming 65 body sinks owing to its weight and to the load which may result from water flowing over the damming body. The water pressure in the weir chamber may be regulated by hand or automatically in any 70 well-known manner by sluices, slide-valves, siphons or the like.

The thickening of the partition walls serves the following purposes:

1. The necessary cross-section is obtained 75 for absorbing the radial forces of pressure. 2. The span of the roof *b* is reduced in the very place where the water pressure is greatest in upright position. 3. The forces transmitted by the ribs *c* to the shaft are distributed over a greater length, thereby reducing the surface pressure or enabling one to use smaller shaft diameters for a given surface pressure. The two extreme partition walls *Ce* may be arranged closer one 80 to the other and connected by the walls *m* so as to form a girder resisting the outer water pressure (see Fig. 3).

The crest of the dam may be formed by a pipe *d* embedded in the concrete, and 90 warm air may be led through said pipe so as to prevent ice from forming. In movable hollow dams of smaller sizes the hollow spaces *f* required for raising the movable dam, can be made so large as to take up 95 the whole of the cross-section of the movable portion. The damming body then assumes the form shown in Fig. 4. It forms a hollow body closed on all sides and receiving outer water pressure only.

100 The exact circular form of the breast-surface *a* may be obtained as follows (see Figs. 5 to 9): Round iron bars (1) are embedded in the concrete partition walls *c*, the projecting ends of said bars being threaded. 105 These round iron bars carry angle irons (2) between double nuts 3. The angle irons are previously bent according to templets and adjusted by means of the nuts in such a way that their front edge lies exactly in the 110

final surface of the ready floated sector. The exact position of these angle irons is checked by a gage made up of the bars 4 with a cross-bar 5 and rotatable about the shaft h which has been previously set in. Wherever it is necessary, the angle irons are corrected by means of the double nuts 3, whereupon the plaster or cement is put on and smoothed afterward by a lath extending over two angle irons. In this way an exactness up to half a millimeter can be attained.

The above described invention enables one to construct movable damming bodies of extremely large sizes (up to 16 meters damming height and even more, with any desired widths) at relatively small cost, and to move them without any special mechanical lifting devices.

I claim—

- 20 1. A movable dam having a horizontal axis of rotation, said dam sector-shaped in cross section and having walls of ferro-concrete, and transverse partition walls thickening toward the axis of rotation.
- 25 2. A movable dam having a horizontal axis of rotation, said dam sector-shaped in cross-section and having walls of reinforced

concrete, a longitudinal partition wall forming a chamber at the dam crest, and transverse partition walls thickening toward the 30 axis of rotation.

3. A movable dam having a horizontal axis of rotation, said dam sector-shaped in cross-section and having walls of reinforced concrete, a longitudinal partition forming 35 a chamber at the dam crest, and auxiliary vertical partitions subdividing said chamber into smaller chambers, and partitions extending from said longitudinal partition and thickening toward the axis of rotation. 40

4. A movable dam having a horizontal axis of rotation, said dam sector-shaped in cross section and having walls of reinforced concrete, and means for heating the dam crest. 45

5. A movable dam having a horizontal axis of rotation, said dam sector-shaped in cross-section and having walls of reinforced concrete and a heater pipe embedded in the concrete at the crest of the dam. 50

In testimony that I claim the foregoing as my invention, I have signed my name.

OTTO SOMMER.
